UNITED STATES PATENT OFFICE.

CHARLES E. ADAMSON, OF BUFFALO, NEW YORK, ASSIGNOR TO ADDRESSOGRAPH COMPANY, OF CHICAGO, ILLINOIS, A CORPORATION OF ILLINOIS.

NAME-PLATE FOR DUPLICATING-MACHINES.

1,242,117.

Specification of Letters Patent.

Patented Oct. 9, 1917.

Application filed October 8, 1914. Serial No. 865,708.

To all whom it may concern:

Be it known that I, CHARLES E. ADAMSON, a citizen of the United States, residing at Buffalo, in the county of Erie and State of New York, have invented certain new and useful Improvements in Name-Plates for Duplicating-Machines, of which the following is a specification.

My invention relates to improvements in printing devices and more particularly to name plates adapted for use in printing machines, or what are commercially known as duplicating machines for printing imitation type-written letters.

In duplicating machines, provision is made for inserting name plates before each printing operation and removing the same after printing operation so that the body of the letter may be printed and with each impression thereof a different name, address, and if desired, salutation may be printed therewith.

Name plates of this type have heretofore been too expensive for general use, and it is the primary object of my invention to provide a simple and inexpensive construction in which a plurality of type units may be assembled to print a name, address and salutation.

To this end the invention consists in a name plate having a body portion provided at one end with an integral spacing flange and at its other end with a removable clamping member provided with an integral spacing flange, said clamping member retaining the assembled type units within the body portion, which latter is slotted to receive said type units and also serves to hold the name plate elevated so that when they are stacked in a pile, those above and beneath will not come in contact with the type.

In the drawings,

Figure 1 is a plan view of a name plate constructed according to this invention.

Fig. 2 is a transverse section taken on line 2-2, Fig. 1.

Fig. 3 is a detached perspective view of the body portion of the name plate.

Fig. 4 is a detached perspective view of the removable clamping member.

The name plate is constructed of sheet metal of the required gage to assure rigidity of the same, and it comprises a body portion A and a removable end clamping portion B.

The body portion is of oblong shape and at one end has a downwardly and inwardly-directed spacing and supporting flange C which serves to stiffen the body portion and at the same time hold said body portion elevated. The body portion is provided with a plurality of transversely-disposed slots D which extend from one end thereof to within a short distance of its other end, and while I have shown two slots, any additional number may be used, depending on whether or not a street address is desired or whether the salutation is to be printed separate from the body portion of a letter.

In the drawings I have shown only the name of the addressee and city residence, but where a street address is desired to be printed, an additional slot will be required, and where a salutation is to be printed with the name and complete address of the addressee, a fourth slot will be required.

As it is difficult to read the name and address from the type, the name plate is provided with a blank space above the slots, and on this space may be secured in any suitable manner a card K on which the name and address is printed so that the same can be easily read.

In each of the slots D the type units E are assembled to provide the desired matter and these type may be held in the slots by suitable retainers F which may be formed approximately like the type units but are of yielding material so as to prevent movement lengthwise in the slots.

The removable clamping member B is formed of a strip of metal bent upon itself, as at G, to provide two parallel clamping walls H separated by a space of a size to snugly receive the unflanged end of the body portion A, the said end being clamped between said walls H in a manner to prevent accidental removal of the clamping member from said body portion. To facilitate the entrance of the unflanged end of said body portion into the clamping member, the upper wall H is flared, as at I. The lower wall H is somewhat wider than the upper wall H and provided with a right angular extension J which serves as a supporting flange and co-operates with the flange C of the body portion to hold the latter elevated, thus permitting the name plates to be stacked in a pile without having the faces of the type

units come in contact with any portion of the name plate above. The type may be easily disassembled by grasping the removable clamping member and drawing the same outwardly to disengage it from the body portion and then draw the type units out of their retaining slots. Other type units to form another name, address, and salutation if desired, may be as quickly inserted in the slots and retained by the retaining members F, after which the removable end clamping member may again be forced over the unflanged end of the body portion to securely hold the type within their receiving slots and also hold the metal of the body portion between said slots in alignment in a rigid manner. The type units may be adjusted lengthwise in the slots as may be desired, usually the lines formed by the assembled type in the slots being given a step arrangement.

Having thus described my invention, what I claim is,—

1. A printing device comprising a body portion having type receiving slots opening from one end of said body portion inwardly to a point near the opposite end and a bent metal clamping member engaging the upper and lower sides of said body portion and extending about the end thereof, whereby the free end of said body portion between said slots are wholly inclosed.

2. A printing device comprising a flat body portion formed of sheet metal having parallel slots extending from a point near one end of said body portion to its other end, and a removable clamping member formed of a strip of metal bent upon itself to provide two spaced walls engaging respectively the opposite sides of said body portion and extending about the end thereof, whereby the free ends of said body portion between said slots are wholly inclosed.

3. A printing device comprising a body portion having type receiving slots extending through one end and a bent metal clamping member wholly inclosing and protecting the slotted end of said body portion and having a flared opening at its inner edge to permit the clamping member to be readily arranged in clamping relation to said body portion.

4. A printing device comprising a body portion having type receiving slots extending through one end, and a bent metal clamping member having spaced sides engaging the top and bottom, respectively, of said body portion and a closed edge, said member wholly inclosing the slotted end of said body portion and extending throughout the length of said end.

5. A printing member comprising a body portion having type receiving slots extending through one end, and a bent metal clamping member inclosing the slotted end

of said body portion and having a wall projecting inwardly and engaging the respective sides thereof and a closed outer edge.

6. A printing device comprising a body portion having type receiving slots extending through one end, and a bent metal clamping member having a wall projecting over each side thereof and a closed outer edge, the upper wall being narrower than the lower wall.

7. A printing device comprising a body portion having type receiving slots extending through one end, and a clamping member having an upper and a lower wall and a closed outer edge, the upper wall being narrower than the lower wall and having its edge turned up to provide a flared opening between said edge and said lower wall to receive and wholly inclose the slotted end of said body portion.

8. A printing device comprising a body portion having a flange at one end and type-receiving slots extending through its other end, and a clamping member inclosing the slotted end of said body portion and having a flange corresponding with the flange on the body portion.

9. A printing device comprising a body portion having a flange at one end thereof and type-receiving slots extending through its other end, and a clamping member inclosing the slotted end of said body portion and having a flared opening to receive said end and a flange corresponding with the flange on the body portion.

10. A printing device comprising a body portion having a flange at one end and type-receiving slots extending through its other end, and a clamping member inclosing the slotted end of said body portion and having an upturned upper edge and a flanged lower edge.

11. A printing device comprising a body portion formed of metal and having one end bent to provide a supporting flange, said body portion having parallel slots arranged at right angles to said supporting flange and extending from a point distant from said supporting flange to the opposite end of said body portion, and a removable clamping member formed of a strip of metal bent upon itself to provide two spaced walls, one wall being flared upwardly and the other being bent at a right angle to provide a supporting flange, the unflanged end of said body portion being adapted for insertion between the spaced walls of said clamping member.

12. A printing device comprising a flat body portion formed of sheet metal having one of its ends bent to provide a supporting flange and having parallel slots opening from the other end and terminating between said ends, and a removable clamping mem-

ber adapted to engage the unflanged end of said body portion, said removable clamping member being formed of a strip of metal bent upon itself to provide two spaced walls of different widths, the upper wall being narrower than the lower and having its free marginal portion flared upwardly and the lower wall terminating in a right-angled extension coöperating with the support-
ing flange of the body portion to hold the printing device elevated.

In testimony whereof I affix my signature in presence of two witnesses.
